UNITED STATES PATENT OFFICE.

CECIL VINCENT STEVENSON, OF SYDNEY, AND HENRY BURGESS, OF PADDINGTON,
NEW SOUTH WALES, AUSTRALIA; SAID BURGESS ASSIGNOR TO SAID STEVENSON.

ELECTRIC RADIATOR.

1,339,935.

Specification of Letters Patent. Patented May 11, 1920.

Application filed June 12, 1918. Serial No. 239,564.

To all whom it may concern:

Be it known that we, CECIL VINCENT STEVENSON and HENRY BURGESS, subjects of the King of Great Britain and Ireland, residing at 605 George street, Sydney, in the State of New South Wales, Commonwealth of Australia, and 182 Windsor street, Paddington, in the State aforesaid, respectively, have invented certain new and useful Improvements in Electric Radiators, of which the following is a specification.

This invention relates to electric radiators employing heating elements of a type comprising a cone of refractory material about 5 which is a helical groove in which is wound a coil of high electrical resistance which becoming heated by the passage of the current imparts its heat to the cone, causing the latter to glow.

0 And the object of the invention is to effect certain improvements in or relating to the cone, its construction and attachment 10s, and to the electrical contacts, whereby by the intimate association of the heating coil with the cone is maintained despite the expansion of the former by heat, whereby the fitting of the cone in a radiator is so simplified as to require no expert knowledge so that new cones complete may be supplied 15 separately and fitted by any person of ordinary skill and intelligence, and whereby in conjunction with a three way switch three variations of heating effect may be obtained with corresponding variation of current consumption.

With these objects in view the invention consists firstly in the form and arrangement of the groove or grooves about the cone and in the attachments relating to the fitting of the cone in the radiator; secondly, in the arrangement of electrical contacts; and thirdly, in the provision where required or desired of two separate grooves on the cone and a resistance coil in each groove, the arrangement of the required connections, and the association therewith of a three way switch whereby said coils may be connected in series or in parallel or one coil only may be in use, to give minimum maximum or medium heating effect respectively as may be required or desired, all substantially as hereinafter described with reference to the accompanying drawings, and more particularly specified in the appended claims.

In the drawings:—

Figure 1 is a perspective view of a radiator with heating elements according to this invention, having two resistance coils, and a three-way switch for regulating the heat- 60

Fig. 2 is a part sectional elevation of the radiator taken through the cone and its attachment, and also showing the three-way switch in diagrammatic form; and 65

Fig. 3 is a sectional elevation on line 3, 3, of Fig. 2. Fig. 4 being a similar view on line 4, 4, of Fig. 2 looking in the reverse direction.

Fig. 5 is a diagrammatic view of the wiring arrangement and of the three-way switch, one coil being shown heavier than the other, merely for the sake of distinction.

The cone 10 is provided with a plug 11 attached thereto by metal bolts 12 and 13 75 the nuts of which constitute terminals 14 and 15 heat insulating washers 16, 16, being interposed between said cone and plug so that the latter is kept comparatively cool. The plug 10 is provided peripherally with 80 a screw-thread of coarse pitch formed on a metal cylinder 17 affixed to said plug in known manner and having a segment 18 inverted over the end of the plug to underlie and make electrical contact with the disk- 85 head 19 of bolt 12. The said cylinder 17 engages and makes electrical contact with a female threaded cylinder 20 secured within a cylindrical socket 21 attached to the framing 22 of the radiator by bolts 23, 23, 90 which also hold the concave reflector 24. The threaded cylinder 20 has also an inverted segment 25 which engages and makes electrical contact with a stud 26 passing through the closed end of socket 21 and to 95 which is attached a terminal 27.

The cone 10 is fitted at its larger and outer end with a grille 28 to which is attached an axial rod 29, and on the exterior periphery of said cone is a helical groove 100 30 (single or double according to whether the radiator is of single or variable heat type), and of which the sides are parallel.

This construction of groove affords greater depth comparatively to width than 105 with an ordinary V groove, the resistance coil or coils are more snugly housed therein and when expanded by heat still remain in close contact with the sides of the groove, and there is less liability of short circuit- 110

ing by a convolution mounting its groove and contacting with an adjoining convolution.

One of said resistance coils 31 is connected to terminal 14 on bolt 12 and to the axial rod 29, while the other coil 32 is connected to terminal 15 on bolt 13 and also to said rod 29. Said rod 29 extends through the plug 11, is terminally rounded and is split at its end to constitute a plug entering and making electrical contact with a socket 34 attached to the main socket 21 and fitted at its end with a terminal 35. The head 36 of bolt 13 projects farther beyond the end plug 11 than that of the corresponding bolt 12, and contacts with an annular metal ring 37 carrying on its rearward face an insulating ring 38 of mica or other appropriate material whereby it is insulated from stud 26. The said ring 37 is attached to and supported by a metal stud 39 engaging a bored and threaded boss integral with said ring, projecting through the socket 21 and fitted externally thereof with a nut constituting a terminal 40.

The switch 41 has terminals A and B to which are respectively connected the main conductors C and D, and also has poles L, M and N. On said terminals A and B are pivoted a pair of associated arms E and F, their free ends being arranged to make contact with the said poles as hereinafter explained. The wiring arrangement from the switch 41 to the radiator (see Figs. 2 and 5) consists of a conductor P from terminal B to terminal 40, a conductor S from pole N to terminal 27 and a conductor T from poles L and M to terminal 35.

This wiring arrangement is suitable for alternating or direct current.

In Fig. 1 the switch 41 is set with terminals A and B respectively connected to poles L and N, the current flow for that setting being by conductor T to terminal 35 socket 34, rod 29, resistance coil 31, bolt 12, threaded cylinders 17 and 20 and stud 26 to terminal 27, thence by conductor S to switch pole N arm F and terminal B and (or) vice versa; also the current flows from terminal 35 through rod 29, resistance coil 32, bolt 13, plate 37, stud 39 to terminal 40, thence by conductor P to switch terminal B and (or) vice versa. In this setting the coils 31 and 32 are operated in parallel to produce maximum heating effect.

In Fig. 2 switch 41 is set with terminal A connected to pole M, the current flow being by conductor T to terminal 35, rod 29, coil 32, bolt 13, ring 37, stud 39 and terminal 40, thence by conductor P to switch terminal B and (or) vice versa. In this setting one coil only is operated, thus providing medium heating effect.

In Fig. 5 switch 41 is set with terminal A connected to pole N the current flow be-

ing by conductor S to terminal 27 thence as before through coil 31 to rod 29 (which however is cut out), and from rod 29 through coil 32 as before to terminal 40, thence by conductor P to switch terminal B, and (or) vice versa. In this setting the coils 31 and 32 are operated in series to produce minimum heating effect.

It will be obvious that by eliminating terminal 40, stud 39 and ring contact 37, and by employing one resistance coil only and an appropriate simple switch, that the same general construction provides a single heat radiator.

It will also be obvious that the heating element comprising cone with coil or coils, and plug with threaded cylinder, requires only to be screwed home in the socket, the necessary electrical contacts being automatically made.

What we claim and desire to secure by Letters Patent is:

1. A heating element for an electric radiator, comprising a cone of refractory material having about its periphery a resistance coil laid in a helical groove, a plug of refractory material on the smaller end of said cone, an externally threaded cylinder constituting a contact making element about said plug and having a segment inturned over the end of said plug, through bolts connecting said plug and cone, one of said bolts engaging said inturned segment and electrically connected to one end of said coil, and in said plug a central rod constituting a contact making element electrically connected to the other end of said coil.

2. A heating element for an electric radiator, comprising a cone of refractory material having about its periphery two resistance coils laid in separate helical grooves, a plug of refractory material on the smaller end of said cone, an externally threaded metal cylinder constituting a contact making element about said plug and having a segment inturned over the end of said plug, a pair of through bolts connecting said plug and cone, one of said bolts engaging said inturned segment and electrically connected to one end of one of said coils while one end of the other coil is connected to the other bolt, and a central rod constituting a contact making element to which the other ends of said coils are connected.

3. A support having a socket, a sheet metal lining in the socket and formed with a screw thread, and a binding post on said socket and securing said lining in place, in combination with a plug having a sheet metal cylinder therearound provided with a thread to engage in that of the lining and with a bolt extending through the plug and securing said metal cylinder thereto; a

heating element comprising a cone of refractory material and a resistance coil on said cone, the smaller end of the cone and one end of the coil being connected to the post, a central rod extending through the cone and through the core and connected to the other end of the coil, a second binding

post on the socket, and means to detachably and electrically connect said second binding post to the said central rod.

Signed at Sydney, N. S. Wales, this tenth day of May, 1918.

CECIL VINCENT STEVENSON.
HENRY BURGESS.
